(57) **CLAIM**

The ornamental design for a toy vehicle loop, as shown and described.

DESCRIPTION

FIG. 1 is a perspective view of a new design for a toy vehicle loop;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a bottom perspective view thereof;

FIG. 9 is a perspective view of another embodiment of the design for a toy vehicle loop;

FIG. 10 is a front view thereof;

FIG. 11 is a rear view thereof;

FIG. 12 is a left side view thereof;

FIG. 13 is a right side view thereof;

FIG. 14 is a top view thereof;

FIG. 15 is a bottom view thereof; and,

FIG. 16 is a bottom perspective view thereof.

The broken lines shown represents portions of a toy vehicle loop and form no part of the claimed design.
